INVENTOR,
Ernest Wolff,
BY *Edgar Gatehouse.*
ATTORNEY.

UNITED STATES PATENT OFFICE.

ERNEST WOLFF, OF NEW YORK, N. Y.

TOY DRUM.

No. 913,798.

Specification of Letters Patent. Patented March 2, 1909.

Application filed March 28, 1908. Serial No. 423,318.

To all whom it may concern:

Be it known that I, ERNEST WOLFF, a citizen of the United States, and residing at New York, in the county of New York and State 5 of New York, have invented certain new and useful Improvements in Toy Drums, of which the following is a specification, such as will enable those skilled in the art to which it appertains to make and use the same.

10 This invention relates to toy drums in which the heads are composed of sheet metal, and the object thereof is to provide a drum of this class which may be played by a child by simply moving the sticks transversely 15 of one of the heads of the drum.

The invention is fully disclosed in the following specification, of which the accompanying drawing forms a part, in which the 20 separate parts of my improvement are designated by suitable reference characters in each of the views, and in which;—

Figure 1 is a plan view of one head of a toy 25 drum constructed according to my invention, and;—Fig. 2 a transverse section on the line 2—2 of Fig. 1.

In the practice of my invention, I provide a toy drum *a*, the body portion of which is preferably composed of sheet metal, and provided with heads *b* also composed of sheet 30 metal, and in the form of construction shown the heads *b* are counter-sunk in the ends of the body portion of the drum. The heads *b* are also provided, in the form of construction shown, with an outwardly directed 35 flange or rim *b*² folded over the ends of the body portion of the drum as shown at *b*³, but my improvement is not, in any way, limited to the method of connecting the heads *b* with the body portion of the drum, and this may 40 be done in any desired manner.

In my improvement, as shown, one of the heads *b* is provided with parallel corrugations *b*⁴ forming corresponding parallel grooves, and the said corrugations and corresponding grooves are formed in the said 45 head by a suitable die or press before the head is secured in the body portion of the drum. In playing my improved drum, all that is necessary, is to pass the drum sticks rapidly over the corrugations *b*⁴ in either direction, or by passing said drum sticks backwardly and forwardly across said corrugations, and this may be done without any previous experience or practice, and a very 50 pleasing result is produced, and a little practice will enable the operator to play almost any tune or air on the drum.

Having fully described my invention, what I claim as new and desire to secure by Letters Patent, is;—

1. A drum comprising a single cylindrical body provided with two heads one of which is metallic and provided with transverse parallel corrugations forming parallel ridges and corresponding parallel grooves. 65

2. A drum comprising a single cylindrical body provided with two metallic heads one of which is provided with transverse parallel corrugations forming parallel ridges and corresponding grooves. 70

In testimony that I claim the foregoing as my invention I have signed my name in presence of the subscribing witnesses this 25th day of March 1908.

ERNEST WOLFF.
